COAL BUCKET DUMPING MACHINE

Filed July 26, 1924

2 Sheets-Sheet 2

Fig. 7. Inventor:
Norman H. McClevey
By Joseph A. Minturn
Attorney.

UNITED STATES PATENT OFFICE.

NORMAN H. McCLEVEY, OF PETERSBURG, INDIANA.

COAL-BUCKET-DUMPING MACHINE.

Application filed July 26, 1924. Serial No. 728,314.

To all whom it may concern:

Be it known that I, NORMAN H. McCLEVEY, a citizen of the United States, residing at Petersburg, in the county of Pike 5 and the State of Indiana, have invented a new and useful Improvement in Coal-Bucket-Dumping Machines, of which the following is a specification.

This invention works in conjunction with 10 the coal loading bucket used in my improved coal mining system, for which I filed application for patent on July 14, 1924, Serial No. 725,852, and the object of the present invention is to transfer the coal 15 from the bucket to cars for removal from the mine without spilling the coal, or delaying the return of the bucket for reloading.

A further object is to provide a loading 20 device which is so readily portable that it can be conveniently moved in keeping with the removal of the vein of coal being mined, and which can be easily adjusted to the different roof and floor conditions of the 25 mine.

I accomplish the above, and other minor 30 objects incidental thereto which will hereinafter appear, by the mechanism illustrated in the accompanying drawings, in which

Fig. 1, is a side elevation of my invention with the bucket shown in position to dump its load upon a conveyor that discharges into a car. Fig. 2, is a top plan view of the same with the bucket removed 35 and also showing the motor and mechanism for operating the conveyor. Fig. 3, is a cross section on the lines 3—3 of Figs. 1 and 2. Fig. 4 is a cross section on the line 4—4 of Figs. 1 and 2. Fig. 5 is a section similar 40 to one side of Fig. 3, but on a larger scale, and showing the conveyor mechanism including its flanged wheels and their tracks. Fig. 6 is a fragment in top plan of the 45 conveyor and Fig. 7 a side elevation of same. Fig. 8, is a perspective view of the rear portion of the conveyor showing the jack-pipes for raising and lowering same. Fig. 9, is a side elevation of my bottomless 50 bucket open at the front end. Fig. 10 is a top plan view of same and Fig. 11, is a front end view of the bucket.

Like characters of reference indicate like 55 parts in the several views of the drawings.

Coal to be loaded on car 12 is gathered in a bucket 13, which is drawn toward the

car by a cable 14, one end of which is hitched to the front end of the bucket, and the other end is made fast to and is wound upon the rotating drum of a hoisting machine (not shown) which may be located at one side as indicated in Fig. 2 by the aid of an idler pulley in block 15, or which may be in direct alignment with the travel of the bucket. A second cable 16, has one end 60 fastened to the rear of the bucket. It passes thence to and around a tail-block (not shown) beyond the far limit of travel of the bucket and thence around the idler pulley in block 15, and thence to a second rotating drum of the hoisting machine, upon which drum it is wound in a manner to move the bucket 13 away from car 12. 65

My loading device is mounted on a rectangular metal base frame 17 on which are 70 two opposite substantial standards 18, supported by diagonal braces 19. These standards are connected by a channel bar 20, from which jack-pipes 21, 21, extend in opposite oblique directions to the roof as 75 braces to hold the device securely where it is placed. Fastened to the bar 20 is a plate 22, with holes for the attachment thereto of pulley block 15, when the hoisting engine is located laterally, to right or left, 80 of frame 17. Each side of the frame 17 also supports the opposite end standards 23 and intermediate standards 24'. Jack-pipes 21, 21, are shown as extending from standard 23 diagonally to the roof to additionally 85 hold the frame. 90

Angle bars 24, are rigidly attached to each set of standards 23, 24, and 18, presenting lower inside flanges which help to form bucket slides. These bars start from 95 about the mid-height of standards 23 and slope upwardly as shown to standards 18, and the spaces above the bars are closed by side plates 25, to keep coal that may be pushed ahead of the bucket from spilling 100 out.

Riveted or otherwise securely fastened to the lower flanges of the bars 24, 24, are the respective metal plates which have horizontal portions 26 to complete the bucket 105 slides at these locations, inwardly oblique portions 27 acting like hopper sides to concentrate the coal, and vertical portions 28, to lap with marginal conveyor flanges and prevent coal spillage there. A pit is thus 110 formed in the oblique bottom supported by the angle bars 24 into which coal, conveyed

- 2
- there in the bottomless bucket 13, is discharged by gravity. The end of approach to the pit has the oblique hopper formation 29 adjacent the standards 23.
- 5 A sloping floor 30, extends from the mine floor to the floor plate 31, supported by the angle bars 24, and the floor 30 has vertical sides 32, 32, that diverge from standards 23 to provide a flaring approach that will
- 10 cover a wider bucket path than an approach would, that was not so flared, and thereby directs the bucket to the dumping pit above, from any line of travel that the bucket may be taking. A pair of angle-bars 42, 42, with
- 15 inturned lower flanges form a track for the rollers of a linked metal-plate conveyor, and a like lower pair of angle-bars 43, 43, form the return track.
- A rear conveyor boom 33, has its outer end
- 20 swingingly adjustable in a vertical plane, from the rear end of the pit, opposite standards 18, and terminating above a car 12, which is one of a series of cars to be loaded with coal for conveyance on a track 35 to
- 25 the hoisting shaft and thence out of the mine, in the usual manner.
- A pair of channel bars 36 extend longitudinally of the boom and swing upon the rollers 37. Sheet metal sides having vertical members 38 and downwardly sloping members 37 terminating between the conveyor flanges, are secured by angle plates 39 to the top of the respective channel bars 36. Angle bars 41 are secured to the channel bars 36 and form a track for the top members of the conveyor.
- Angle-bars 40, are secured by plates 48, to the under flanges of the respective bars 36, with the channels of bars 40 turned inwardly so their lower flanges form a track for the conveyor in its return.
- A pair of jack-pipes 21, one for each side of the boom, bear upon the frame 17, and against the bars 40. They have wheels connected by a sprocket chain 41', whereby the screws will be operated simultaneously and the same, to raise or lower the boom to suit varying floor and roof conditions of the mine.
- 50 A continuous conveyor formed of metal plates 44, riveted at one edge of each plate to a shaft 45, and united by links 46, has flanged rollers 47, mounted on the projecting ends of the shafts 45. The rollers in the upper portion of the conveyor, travel upon the tracks 42 and 40, and in the lower portion of the conveyor the rollers travel in a reverse direction upon the tracks 41 and 43. The plates are preferably curved transversely in the usual manner, to pass freely around the end wheels, and are curved near their longitudinal edges to fit close to the shaft; they also have end flanges 48, to aid in preventing spillage of coal between the conveyor and the adjacent hopper sides.
- The upper end of the conveyor passes around wheels 51 on a shaft 50, supported in bearings on the channel bars 36, and the lower end of the conveyor passes around wheels 52 on a shaft 53, supported in bearings 70 mounted on the base frame 17 and on a frame extension 54 from the latter. The shaft 53 is in two parts which are united by a friction clutch 55, manipulated by a hand-lever 56, and the shaft is driven from a motor 57 in any usual and suitable manner.
- The operation of my invention is as follows: Coal gathered in the bucket 13 is drawn by cable 14 to and up the inclined floor 30. The flaring sides 32 direct the bucket between the side plates 25. The travel of the bucket is continued to the position in which it is shown in Fig. 1, which is over the pit in the floor supporting the bucket, and the coal in the latter is deposited by 85 gravity upon the endless conveyor at the bottom of the pit. The bucket is then returned without delay for refilling, and the travel of the conveyor carries the coal deposited upon it from the bucket upwardly 90 of the boom and at the turn of the conveyor drops it off into a car below which has been pushed into right position to secure it.
- The movement of the conveyor is always 95 under control by an operator stationed at the hand lever 56, so that when a car is full the conveyor is unclutched from the motor and stops discharging coal until the full car is replaced with an empty one. Spillage of coal at the sides of the conveyor is 100 prevented by the guards, as described.
- When coal is to be gathered from positions too far to one side of my apparatus for convenient operation thereof, as the progressive working of the mine will make of 105 frequent occurrence, the jack-pipes to the roof and other anchorages, if any, will be removed and a hitch of the bucket-ropes made to the base frame, and thereupon the loading device as a unit will be hauled over 110 to such new position as may be desired, and there held by replacing the jack-pipes and other stays.
- 115 While I have here shown and described my invention in detail, it is obvious that many variations in structure are possible without departing from the spirit of the invention, and I therefore do not desire to be limited to the construction shown, or to any precise form more than is required by 120 the appended claims.
- I claim:
1. In a coal gathering and loading device, a bottomless bucket in which the coal is gathered and transported by sliding the bucket over a surface, a raised floor having a pit over which the bucket is slidingly moved and its contents discharged by gravity into the pit, an inclined surface from the floor 125 of the mine to the raised floor having raised

sides that converge toward the raised floor and an endless apron conveyor at the bottom of the pit receiving and transferring the coal and discharging it at its return end.

5 2. In a coal gathering and loading device, a bottomless bucket in which the coal is gathered and transported by sliding the bucket over a surface, a raised floor having a pit over which the bucket is slidingly moved and its contents discharged by gravity into the pit, an inclined surface from the floor of the mine to the raised floor having raised sides that converge toward the raised floor, and an endless apron 10 conveyor at the bottom of the pit receiving and transferring the coal and discharging it at its return end, said conveyor having outward marginal flanges and fixed sides cooperating therewith to prevent spillage of 15 coal laterally of the conveyor.

3. In a coal gathering and loading device, a coal gathering bucket having means for discharge through its bottom, a floor raised above the mine floor having a pit 20 and raised sides, a sloping approach from the mine floor to the raised floor having raised sides which converge to the raised sides of the raised floor, a conveyor apron extending under the pit and receiving coal discharged through the bottom of the bucket when the bucket is on the raised floor, said apron having marginal flanges, and cooperating plates depending from the rest of the machine to prevent spillage of coal laterally of the conveyor.

35 4. In a coal gathering and loading device, a coal gathering bucket having an open

front and bottom, a floor raised above the floor of the mine having a pit and raised sides, a sloping approach from the mine floor 40 to the raised floor contracting in width toward the latter and having raised sides, means for sliding the bucket along the mine floor and up the approach to a position over the pit in the raised floor, a travelling endless conveyor at the bottom of the pit securing the coal discharged therein from the bucket and conveying it above and discharging it into a car, the discharge end of the conveyor being vertically adjustable to varying 45 mine roof and floor conditions.

5. In a coal gathering and loading device, a coal gathering bucket having an open front and bottom, a floor raised above the floor of the mine having a pit and raised sides, a sloping approach from the mine floor 50 to the raised floor contracting in width toward the latter and having raised sides, means for sliding the bucket along the mine floor and up the approach to a position over the pit in the raised floor, a travelling endless conveyor at the bottom of the pit securing the coal discharged therein from the bucket and conveying it above and discharging 55 it into a car, the discharge end of the conveyor being vertically adjustable to varying mine roof and floor conditions, and means for stopping the travel of the conveyor at the will of an operator.

Signed at Indianapolis, in the county of Marion, and State of Indiana, this 24th day of July, 1924.

NORMAN H. McCLEVEY.
